SYRINGE APPLIANCE

Michael E. Demsey, Cleveland, Ohio

Application July 19, 1940, Serial No. 346,297

4 Claims. (Cl. 128—249)

My invention pertains to a syringe appliance to be used by itself, if of suitable size, or in combination with a support through which it may siphon or discharge and which support might be an eye-cup or a bottle closure.

The subject matter of this application constitutes a continuation in part from the disclosure of my application entitled, "Medication appliance," filed August 12, 1939, Serial No. 289,886, now Patent No. 2,209,192, dated July 23, 1940.

In that identified patent, both the syringe structure and the support are composite or assembled; however an integral eye-cup and screw cap, though illustrated, is not claimed. The originations herein disclosed, while comprehending the same principles of function, are improvements principally based on commercial considerations and involve integrality not only of a combined eye-cup and bottle cap enclosed thereby, but also integrality of the syringe proper which in its entirety is exemplified as composed of a soft molded rubber.

The primary object of my invention has been to provide a uniquely compact syringe structure, economical of manufacture and more readily assembled with a support, whether the latter be an apertured eye-cup, an apertured bottle cap or a combination of both cup and cap or a combination of an eye-guard and bottle stopper. A further object has been a realization of extended possibilities for enduring color variation both of the rubber syringe and of the support which is perhaps to be formed as a molded plastic.

Adverting to the drawing:

Figure 1 is an elevation of my appliance, partly broken away, mounted on a bottle top.

Figure 2 is a diametrical sectional view of Figure 1.

Figure 3 is a bottom plan view of my syringe appliance detached from the bottle neck.

Figure 4 is a perspective view of a modified form of the syringe by itself, circumferentially arranged radial projections appearing substituted for an inner flange of annular shape as shown in Figure 2.

Figure 5 is a view corresponding to Figure 2, illustrating a further modification, alike of the syringe proper, of the carrying support and of the manner of effecting detachable connection with a bottle or other container.

A concavo-convex eye-cup 1 is of conventional shape except that its central or head portion 2 is provided with a central aperture 3 and except further that it is provided interiorly with (as exemplified, integral therewith) an annular

flange 4 which is completely enclosed by the eye-guard or cup and projects toward its larger and permanently open end. The flange 4 is internally fashioned with screw threads 5 adapted to cooperate with external complementary screw threads 6 around the neck 7 of a bottle whereby the annular flange 4 may serve the function of a bottle-cap closure. The aperture 3 is defined by an annular flange 8 lying in a plane perpendicular to the longitudinal axis of the cup to provide an inner annular surface 9 which extends radially outward to the cap 4. The purpose of the annular surface 9 presently will be explained. The structure described in this paragraph will 15 be composed, as currently contemplated, of a plastic or other moldable substance like rubber or Celluloid.

An internal syringe structure 10, necessarily hollow, has been successfully manufactured and 20 marketed as a composition of soft and readily distortable or deformable rubber. It comprises a short neck portion 11 intended to have a snug, frictional fit within the aperture 3, an exterior shoulder or flange 12 which has a flat surface 25 for abutment against the exterior, annular surface of the head 2 and an interior, terminal flange 13 of slightly smaller circumference than the radially outward circumference of the annular surface 9. The inner syringe flange 13 is 30 thin enough to permit of its folded displacement or temporary distortion to smaller compass preparatory to pressing it through the aperture 3 and permitting it to expand to its normal position in which it appears in Figure 2 and in 35 which position it is resiliently clamped against the annular surface 9. The length of the neck 11 of the syringe, being about the same or a modicum shorter than the thickness of the annular flange 8 of the head of the eye-cup, accomplishes 40 such a yielding clamping action of the eye-cup head between the spacedly apposited flanges of the syringe. When attached to a bottle neck, the inner syringe flange 13 will become squeezed against the lip of the bottle whereby advantageously to serve the additional function of a 45 sealing gasket. A lining tube 14 extends through the hollow syringe structure and into the confines of a hollow bulb partially defined by a thin, readily flexed and top diaphragm 15, whereby 50 the ordinary functions of a syringe, either to siphon or to discharge, may be exercised. As shown, the lining tube is composed of glass, but other materials would obviously satisfy. The inner end 16 of the lining tube preferably projects a short distance inwardly beyond the inner flange 13

to improve the dropwise deposition of any fluid which has been earlier syphoned into the bulb, and the opposite end of the lining tube 14 is supplied with a flaring bead 17 conforming to the approximately hemispherical side of the bulb which is opposite the diaphragm 15.

The modification illustrated in Figure 4 consists in the substitution for the inner flange 13 of annular form, of a plurality of radial projections 18 somewhat more readily deformed to facilitate the projection thereof through the aperture in the support. The clamping attachment of the syringe is similarly to be effected by the operation of an outer flange or shoulder 19 and diaphragm cover 20.

The modification of Figure 5 involves an elimination of the interior screw cap because the construction is intended for attachment to bottles which are not provided with screw-threaded necks. An eye-cup 21 has an apertured head 22; a syringe structure has a relatively short neck whose length corresponds to the thickness of the head 22, only an exterior enlargement provided with a flat surface 24 abutting the outer side of the head; a longer lining tube 25 occupies the hole 26 of the syringe, but projects a greater distance therefrom into the eye-cup; a rubber stopper 27 having a bore 28 is adapted for frictional envelopment of most of the projecting end of the tube until it abuts the inner side of the head 22 at 29 while a bottle neck 30 is adapted snugly to receive the stopper.

It is to be realized that the novel scope of my invention comprehends many equivalent variations of structure if exercising the same function. The showing of the drawing and the particular descriptions are merely specific exemplifications of a plurality of readily conceivable modifications.

I claim:

1. The combination as an integral structure, of

5 a hollow interiorly threaded cup-shaped member purposed to serve as a bottle closure and an eye guard of comparatively larger concavo-convex form enclosing and secured to the central portion of said member, said structure being provided with a central aperture for introduction of a syringe nozzle and a syringe closure for said aperture.

10 2. The combination as an integral structure, of a member intended to serve as a closure for a container, a concavo-convex eye-cup enveloping said member in spaced relation thereto, said structure being provided with a central aperture for introduction of a syringe nozzle and syringe

15 means for closing said aperture.

20 3. The combination of an eye cup alternatively adapted to enclose the entry of a fluid container and provided with a central opening, a rubber syringe structure comprising a neck occupying said opening and further comprising radially outward projecting means on the inside and outside of said cup respectively for clamping said syringe structure to said eye cup and a lining tube fitted in said neck and projecting beyond the cup-enclosed end thereof.

25 4. The combination with an eye-cup provided with a central aperture, of a rubber syringe structure integrally comprising; a neck adapted to occupy said aperture, intermediately of its ends an annular flange abutting the outside of said eye-cup around its aperture, a flexible diaphragm forming in conjunction with said intermediate section a bulb adapted to syphon and to discharge fluid through said neck and eye-cup and at the inner end of said neck radially outwardly projecting means cooperating with said flange to clamp the syringe and eye-cup together; and means within the eye-cup adapted to serve as a bottle closure.
